INVENTOR
Angelo L. Soresi
BY C. P. Gogel

ATTORNEY

UNITED STATES PATENT OFFICE.

ANGELO L. SORESI, OF NEW YORK, N. Y.

COLLAR.

1,378,142.

Specification of Letters Patent. Patented May 17, 1921.

Application filed August 15, 1919. Serial No. 317,744.

To all whom it may concern:

Be it known that I, ANGELO L. SORESI, a citizen of the United States, and a resident of the borough of Manhattan, in the city, 5 county, and State of New York, have invented certain new and useful Improvements in Collars, of which the following is a specification.

This invention relates to improvements in 10 collars and particularly has for its object to provide a collar which may be worn without impairing the circulation of blood through the blood vessels in the neck of the wearer. A further object is to provide a 15 collar which will be thoroughly comfortable to wear and while embodying features distinct from an ordinary collar, will not be different or unusual in its outward appearance, and will not require any special manner 20 of securing the collar in place or adjusting the tie, the tie space being substantially similar in form and function to that of an ordinary or straight collar.

With these and other objects in view, an 25 embodiment of my invention is shown in the accompanying drawings and this embodiment will be hereinafter more fully described with reference thereto and the invention will be finally pointed out in the 30 claims.

In the accompanying drawings:

Figure 1 shows the head and shoulders of a man wearing a collar according to one embodiment of my invention,

Fig. 2 is a perspective view of the collar in its fastened position as worn;

Fig. 3 is a plan view showing the two 40 folds of the collar flattened out; and

Fig. 4 is a diagrammatic view showing portions of the thorax and blood vessels of the neck and their relation to the bony structure.

Similar reference characters indicate corresponding parts throughout the several figures of the drawings.

Referring to the drawings and more particularly to Fig. 4 thereof in which I have shown diagrammatically, portions of the bones and blood vessels of the lower part of the neck and thorax, the blood vessels extend as at 10 and 11 over the first rib bones 12 and 13 and beneath the clavicle bones 14 and 15. According to my invention, the collar comprising an inner fold 16 and an outer

fold 17 is provided along the lower edge of 55 the inner fold and at each side of the overlapping ends thereof when fastened with arcuate cut-outs 18 and 19 so placed that they extend over and embrace the blood vessels above the first rib, so that pressure thereon is 60 prevented and as a result the collar may be worn with comfort and without interfering with the flow of blood and the consequent injurious effects upon the circulation of the head and neck, the said cut-outs being 65 further constructed so as to correspond in height approximately to the height of an ordinary shirt neck-band as will be obvious from an inspection of Fig. 3 where it will be seen upon inversion of said figure that the 70 highest points of cut-outs 18-19 aline with the openings in the free ends and middle portion of the band 16. With this construction the neck of the wearer is prevented from contacting with the inner face of a 75 cravat or necktie in a way that would cause annoyance to the wearer and increase the friction on the cravat or tie in the operation of adjusting the same. The cut-outs 18 and 80 19 are disposed entirely within the forward quarters of the collar. The remainder of the lower edge 20 of the inner fold is unbroken and when the collar is worn lies substantially parallel and contiguous to the 85 lower edge of the neck band of the shirt.

Notwithstanding the cut-outs, the two folds of the collar provide at each side of the cut-outs a substantial supporting surface for the necktie so that it will not press uncomfortably upon the neck. A proper 90 slide space will be provided for permitting easy slippage of the necktie in tying and the necktie will be correctly maintained in place between the folds in a substantially similar manner to that of a collar having a 95 solid inner fold with an unbroken lower edge.

My improvements, it will be understood, may be embodied also in a collar having a single fold, that is, the so called stand-up 100 collars, in which case the necktie will cover and obscure the cut-outs from view.

In wearing a collar of the usual type having an unbroken lower edge, the collar band of the shirt and the necktie being soft, are 105 inconsequential so far as pressure on the blood vessels is concerned, but the stiff hard edge of the collar bears upon the blood ves-

sels and exerts a very decided pressure thereon with its consequent injurious effects, annoyances and impairment of the circulation. It is this effect that the present invention avoids.

I have illustrated and described a preferred and satisfactory embodiment of my invention, but it is obvious that changes may be made therein within the spirit and scope 10 thereof as defined in the appended claims.

I claim:

1. A collar having its middle and free end portions provided with openings for the reception of means for fastening the collar to the neck band of a shirt, the lower edge of 15 said collar extending uninterruptedly from the said middle and free end portions to oppositely disposed and relatively narrow roached portions, the highest points in 20 which align with the said openings of the collar, said roached portions being arranged so as to avoid transmission of pressure from said edge to the blood vessels of the wearer

extending laterally from the neck and posterior to the uppermost ribs.

2. A fold collar having an inner band and an outer fold, the inner band having its middle and free end portions provided with openings for the reception of means for fastening the collar to the neckband of a shirt, 30 the lower edge of said band extending uninterruptedly from the said middle and free end portions to oppositely disposed and relatively narrow roached portions, the highest points in which align with the said openings of the band, said roached portions being arranged so as to avoid transmission of pressure from said edge to the blood vessels of the wearer extending laterally from the neck and posterior to the uppermost 35 ribs.

In testimony that I claim the foregoing as my invention, I have signed my name hereunder.

ANGELO L. SORESI.
